FOREIGN PATENT DOCUMENTS

ES I01421 13 - X * 12/1998

Primary Examiner — Susan Bennett Hattan*Assistant Examiner* — Leanne Was(74) *Attorney, Agent, or Firm* — Bell Nunnally & Martin LLP; Craig J. Cox(57) **CLAIM**

I claim the ornamental design for a domed cup lid for holding an inverted bottle, as shown and described.

DESCRIPTION

FIG. 1 is a top perspective view of a domed cup lid for holding an inverted bottle;

FIG. 2 is a bottom perspective view of the domed cup lid for holding an inverted bottle shown in FIG. 1;

FIG. 3 is a side view of the domed cup lid for holding an inverted bottle shown in FIG. 1;

FIG. 4 is an opposite side view of the domed cup lid for holding an inverted bottle shown in FIG. 1;

FIG. 5 is a top view of the domed cup lid for holding an inverted bottle shown in FIG. 1;

FIG. 6 is a bottom view of the domed cup lid for holding an inverted bottle shown in FIG. 1; and,

FIG. 7 is a perspective view of the domed cup lid for holding an inverted bottle shown in FIG. 1 shown attached to a cup and holding an inverted bottle.

In all figures, elements shown in broken lines are for illustrative purposes only and form no part of the claimed subject matter.
